UNITED STATES PATENT OFFICE.

HARRY T. KRAKAU, OF CLEVELAND, OHIO, ASSIGNOR TO THE NATIONAL MALLEABLE CASTINGS COMPANY, OF CLEVELAND, OHIO, A CORPORATION OF OHIO.

COUPLING-SUPPORT.

1,099,854.

Specification of Letters Patent.

Patented June 9, 1914.

Application filed June 17, 1911. Serial No. 633,871.

To all whom it may concern:

Be it known that I, HARRY T. KRAKAU, a resident of Cleveland, in the county of Cuyahoga and State of Ohio, have invented 5 a new and useful Improvement in Coupler-Supports, of which the following is a full, clear, and exact description, reference being had to the accompanying drawings, forming part of this specification, in 10 which—

Figure 1 is a view partly in top plan, partly in horizontal section and partly diagrammatic, illustrating my improved coupler support; Fig. 2 is a view of the same 15 on a larger scale, partly in side elevation and partly in vertical section; Fig. 3 is a plan view; Fig. 4 is a section on the line IV—IV of Fig. 3; Fig. 5 is a perspective view of one-half of the supporting stirrup; 20 Fig. 6 is a perspective view of one of the keys; Fig. 7 is a plan view of the carry-iron shoe; and Figs. 8 and 9 are perspective views of key members.

My invention has relation to supports for 25 car couplers, and more particularly for car couplers of the radially swinging type.

Heretofore, it has been customary to provide supports consisting of relatively long radial segments lying beneath the shank of 30 the coupler, said shank being adapted to slide thereon in its radial movement.

According to my present invention, I provide the end sill of the car with a suitable 35 carry-iron support for engagement with a hanger member which, in turn, has a supporting engagement with the coupler shank and preferably with projections on the side of the shank.

The nature of my invention will be best 40 understood by reference to the accompanying drawings, in which I have shown the preferred embodiment thereof and which will now be described, it being premised, however, that various changes can be made 45 in the details of construction and arrangement of the several parts by those skilled in the art, without departing from the spirit and scope of my invention, as defined in the appended claims.

50 In these drawings, the numeral 2 designates the end sill of a car and 3 is a carry-iron support which is bolted or riveted to the front face of the end sill. This carry-iron support is formed with an overhung portion 4 of trough form.

5 designates a coupler head having a rearwardly extended shank 6, secured to a shank extension 7, in any suitable manner, as by the bolts 8. The coupler and its shank extension are arranged to swing radially from 60 a suitably located center, indicated at 9 in Fig. 1.

The bottom wall of the overhung portion 4 of the carry-iron support is formed with an elongated vertical slot 10, and this slot, 65 together with the curved front face of the support, are on arcs of concentric curves struck from the center 9. The front wall of the overhung portion is backed up by suitable reinforcing ribs 11, which are cut 70 away, as shown at 11^a to permit the movement of the coupler-supporting stirrup, hereinafter described. This supporting stirrup is shown at 12. It is made in two symmetrical halves, one of which is shown in 75 detail in Fig. 5. Each of these halves comprises a vertical portion having an inwardly projecting arm 12^a at its top and an inwardly projecting arm 12^b near its lower end. The two halves, when assembled, form 80 a rectangular opening which embraces and entirely surrounds the shank of the coupler, as clearly seen in Fig. 4. The two halves of the stirrup may be secured together in any suitable manner. In the drawings, I have 85 shown the arms 12^a as having T-slots 12^c, to receive a doubled T-headed key 13 (shown in detail in Fig. 6). The lower arms 12^b of the stirrup sections support a carry-iron shoe 14, which rests thereon and is formed 90 with depending lugs 15, which have a sliding engagement with the arms 12^b and are secured by means of keys 16, driven through openings 17 in the arms 12^b and against the inner sides of the lugs 15. The key 13 is 95 secured by the taper keys 18. The keys 16 serve a double purpose of holding the shoe 14 in position to prevent its sliding laterally and of holding together the lower ends of the two halves of the carry-iron stirrup. 100 When the stirrup sections are assembled in the manner described and the keys 16 and 18 are driven to their seats, the two parts of the stirrup are firmly locked together and enclose the coupler shank in the manner described.

105 The inner sides of the vertical legs of the stirrup sections are formed with the inwardly projecting lugs 19, which have a supporting engagement with the lateral 110

flanges 20 of the coupler shank, as clearly shown in Fig. 4. It will be noted that the coupler shank is in this manner held entirely clear of the carry-iron shoe 14 and is supported wholly by the engagement of the lugs 19 with the flanges 20. The purpose of this is to bring the points of support as high as possible and as close as possible to the points of support of the carry-iron stirrup. This greatly facilitates the lateral sliding of the upper portion of the carry-iron stirrup upon the bottom surface of the overhung channel portion of the carry-iron support.

15 As will be seen by reference to Figs. 2 and 5, the upper arms 12^a of the stirrup sections are formed with the lateral flanges 12^a, which rest upon and having a sliding engagement with the bottom surface of the 20 overhung portion of the carry-iron support at each side of the curved slot 10, the vertical edge of the stirrup extending through said slot at each side of the coupler shank.

My invention provides a support for radially swinging couplers which is simple in its construction and which obviates the use of the radial segments commonly employed beneath the shank and coupler, and which, while giving proper support to the coupler, 30 also affords the necessary freedom of lateral movement. It also provides a support which can be readily and quickly applied to and disengaged from the coupler shank.

As before stated, various changes may be 35 made in the construction and arrangement of the several parts. Thus, the carry-iron support, although preferably an integral casting of the form shown, may be made in various other ways; the construction of the 40 supporting stirrup may also be varied and various other changes may be made within the scope of the appended claims.

I claim:

1. The combination with a radially- 45 swinging coupler, of a support therefor comprising a carry-iron secured to the end sill of a car and projecting forwardly therefrom, said carry-iron having a trough portion formed with a curved slot in its bottom 50 wall, and a supporting device having a sliding engagement with the said bottom wall and extending downwardly through the slot and having a supporting engagement with the coupler, said trough portion having an 55 open top to permit removal of the support-

ing device therethrough, substantially as described.

2. The combination with a radially swinging coupler having a shank provided with lateral flanges, of a supporting stirrup 60 embracing the shank and having a supporting engagement with said flanges, together with a carry-iron on which the stirrup is slidably supported, substantially as described.

65 3. The combination with a radially swinging coupler having its shank provided with lateral flanges at the upper edges thereof, of a depending stirrup having projections engaging the under side of said flanges, 70 and a carrying member forming a support for the stirrup, substantially as described.

4. In a support for radially swinging couplers, the combination with a coupler and its shank, a stirrup-shaped coupler-shank support adapted to surround the coupler-shank and having a supporting engagement therewith, the stirrup being comprised of two laterally separable parts depending from a carry iron, and a bottom portion 80 interfitting with the laterally separable parts, the said bottom portion comprising means for securing together the two laterally separable parts, substantially as described.

85 5. In a coupler-support, a carry iron, a stirrup for supporting the coupler-shank depending therefrom, the said stirrup being comprised of two laterally movable, vertically disposed portions and a bottom portion, the bottom portion comprising means for rigidly but separably securing together the parts of the stirrup, substantially as described.

90 6. In a coupler support, a two-part stirrup adapted to form a substantially rectangular structure, and means for rigidly but separably securing together the parts of said stirrup, said stirrup having its side portions provided with coupler supports, substantially as described.

95 7. A radially swinging coupler having its shank provided with lateral extended supporting flanges, substantially as described.

In testimony whereof, I have hereunto set 105 my hand.

HARRY T. KRAKAU.

Witnesses:
